assignors to Appleton Electric Company, a corporation of Illinois

Application August 26, 1935, Serial No. 37,883

11 Claims.

(Cl. 153—9)

The object of the present invention is to produce a simple and novel tool for pressing an annular bead in the wall of a tube of ductile material, usually metal.

The various features of novelty whereby our invention is characterized will hereinafter be pointed out with particularly in the claims; but, for a full understanding of our invention and of its objects and advantages, reference may be had to the following detailed description taken in connection with the accompanying drawings wherein:

Figure 1 is a rear elevation of a tool embodying the present invention, a tube being shown in position in the same; Fig. 2 is a side view of the lower end of the tool, with the pipe shown in end elevation; Fig. 3 is a view similar to Fig. 2 showing the opposite side from that appearing in Fig. 2, the upper or handle part of the tool being shown in section; Fig. 4 is an end or bottom view of the tool; and Fig. 5 is a section on line 5—5 of Fig. 3, showing only the parts that appear in the plane of the section.

Referring to the drawings, 1 represents a C-shaped head whose two arms 2 and 3 are straight and parallel. On the upper side of the lower arm 2 is mounted a short roller 4 which projects upwardly beyond the bearing ears 5 and 6. Extending through the arm 3, and at right angles thereto, is a sturdy bar or slide 7 on the lower end of which is a jaw or fork 8. Mounted between the arms, 9 and 10, of this jaw or fork is a long roller 11 having an annular peripheral groove 12 which registers with the roller 4. In other words, when the bar or slide 7 is dropped down until the rollers engage with each other, the lower roller is engaged in the groove in the upper roller.

In using the device the roller 11 is first retracted sufficiently to permit the tube that is to be beaded to be slipped over the arm 2 of the head. Then, when the roller 11 and its carrier are moved down, the end sections of the roller 11 come in contact with the outer surface of the tube on opposite sides of a short stretch which is resting on the roller 4 and which spans the groove 12. Further downward pressure on the roller 11 will cause the metal of the tube to yield and bend. At first there will be produced a slight dent. Thereupon, if the tube be held stationary and the tool be swung around the same, this indentation will be progressively carried around the entire circumference to the starting point. Therefore, what was originally a slight dent, viewed from the inside of the tube, and a

slight bulge as viewed from the outside, has become a rudimentary annular bead or rib as viewed from the outside and a shallow annular trough as viewed from the inside. By swinging the tool around the tube a number of times, and gradually forcing the rollers together, the metal of the tube is caused to be drawn into the shape of a substantial annular bead whose external contour is determined by the shape of the groove 12 in the roller 11 and the shape of the trough in which depends upon the contour of the peripheral portion of the roller 4.

Attached to the arm 3 of the head and projecting at right angles therefrom, is a handle 13 by which swinging movements are given to the tool. Also, as will hereinafter be explained, the turning of this handle about its axis causes the roller 11 to move from or toward the cooperating roller. The tool cannot be caused to travel round the circumference of the tube unless some means are provided to maintain a radial line passing through the axes of both of the rollers. Having only the parts that have been described, and assuming that a radial line can be drawn which will intercept the axis of the tube and also the axes of the two rollers and that the roller 11 has been forced down so as to produce a slight dent in the tube: it will be seen that when pressure is applied to the handle to swing it either towards the right or towards the left, as viewed in Fig. 2, the rollers will not roll on the wall of the tube but will serve simply as a fulcrum about which the tool as a whole will rock. We have therefore provided means to prevent such rocking movement of the tool. This means comprises an arm 14 which, in effect, is a continuation of the arm 10 of the jaw that carries the roller 11. The arm 14 extends laterally and also downwardly or outwardly well past the top of the roller 4. At the free end of the arm 14 is a long extension 15 that projects inwardly parallel with the axis of the roller 11 and, therefore, the axis of a tube positioned in the tool. The inner edge of this extension is so located that it engages throughout its length with the outer surface of the tube at a considerable angular distance from the line of contact between the rollers and the tube. With this arrangement, when the tool is closed on the tube and is swung in such a direction that the arm 14 is leading or in advance, the tool is prevented from rocking about the point of contact between rollers and the tube, but it must slide bodily along the wall of the tube, the rollers in the meantime turning on their axes and pressing or drawing the wall into the

desired bead formation. As best shown in Fig. 4 the extension or brace 15 has a notch 16 in its inner or working edge, to provide clearance for the bead *a* as the latter develops.

5 Some means should be provided to serve as a stop against which the end face or edge of the tube may be held while the bead is being fashioned. In the arrangement shown, there are two such stops or bearing faces against which the end 10 of the pipe may be thrust. One of these stops is the lower end of the inner arm 9 of the jaw 8 that carries the roller 11; this arm projects far enough beyond the periphery of the roller 11 to lie in the path of a tube that has been 15 slipped on the lower arm of the head of the tool and rests on the roller 4. The other stop is a little lug 17 at the free end of the extension 15 on the arm or brace 14; this lug projecting inwardly or toward the head proper. As best shown 20 in Fig. 1, the working face of the lug 17 lies in the same plane as does the stop face of the arm 9 of the carrier for the roller 11. With this arrangement the tool may be accurately positioned on the tube with the axis of the roller 11 25 parallel to the axis of the tube.

We have found that if the axes of the rollers 4 and 11 are parallel there is a strong tendency to cause a lengthwise feeding movement of the tube in a direction to eject it from the tool. In 30 other words, instead of producing an annular bead extending around the tube in a plane at right angles to the axis of the tube, the tendency is to produce a spiral bead. We have also found that this tendency to screw the tube out of the 35 tool can best be overcome by placing the axis of the roller 4 slightly out of the parallelism with the axis of the cooperating roller, the angular displacement being in a direction to cause a slight tendency to feed the tube farther into the 40 tool or, in other words, forcing the end edge or face of the tube positively against the stops. Thus, viewing the two rollers as they appear in Fig. 1, their axes appear to lie in parallel planes. However, the axis of the roller 4 lies at an angle 45 of a few degrees to a plane extending lengthwise of the tool and containing the axis of the roller 11 and of a tube in the tool.

The periphery of the roller 4 is preferably roughened somewhat, conveniently by forming 50 therein fine transverse grooves 18. This enables the rollers to grip the metal of the tube and provide better traction than is the case when both gripping faces are smooth. Since the roughened roller acts on the inner surface of 55 the tube no evidence of the biting action of this roller is visible on the outer surface of the tube and no marring of that surface can occur.

It will be seen that if the arm or brace 14 fits properly against a tube of a given size it will 60 not do so with respect to a tube of larger or smaller diameter. Therefore, if it be desired to employ the tool on tubes of different diameters, means must be provided to adjust it. A simple way of doing this is to make the arm 14 detachable and provide a series of arms of different sizes which may be interchanged with 65 each other according to the sizes of tubes that are to be beaded. In the arrangement shown, the outer end of the shaft 20 for the roller 11 70 is continued outwardly beyond the arm 10 of the carrier and the member 14 is provided with a hole with which this projecting shaft end fits. Then, at some distance from this point, a screw 21 extends through the member 14 and into the 75 arm 10. Consequently, by removing a single

screw the member 14 may be detached although, when fastened in place, it is securely held.

The handle proper, 13, is a tubular member secured to a neck 22, shown as being integral with the arm 3 of the tool head, in such a manner that the handle and the neck are free to turn relatively to each other about the axis of the handle, but are firmly held against relative movements in other directions. In the arrangement shown, there is a heavy sleeve nut 23 fixed 10 in and projecting beyond the inner end of the handle proper 13. This sleeve nut rests at its free or outer end on the end of the neck 22 and has thereon an annular out-turned flange 24. The neck 22 is externally screw-threaded for 15 some distance inwardly from its free or upper end, as indicated at 25. A coupling sleeve 26 fits rotatably on the projecting portion of the sleeve nut, has an internal shoulder 27 that rests on the flange 24, and is provided with an 20 enlarged internally screw-threaded lower apron section 28 that is screwed upon the screw-threaded part of the neck 22. A set screw 29 may be employed to secure the coupling member 25 against rotation on the neck of the tool head; whereby the coupling member is held in a fixed 30 position without clamping the flange 24 so tightly as to interfere with the freedom of rotation of the handle.

The bar 7 which carries the roller 11 has at 30 its upper end a long externally screw-threaded stem 30 that fits the screw-threaded opening in the sleeve nut 23. Since the bar 7 is held against rotation in the head, as will be explained later, but may slide lengthwise, a turning movement 35 of the handle results in an endwise movement of the bar, in one direction or the other. This endwise movement of the sliding bar carries the roller 11 toward or away from the cooperating roller 4, as the case may be. The main portion of the bar 7 is shown as being square in cross section, and as the bar is slidably fitted in a correspondingly shaped seat in the tool head, the bar may slide but cannot rotate. The seat 31 is preferably in the form of a longitudinal groove 45 cut into the neck member 22 through one side thereof. In order to confine the bar 7 in this groove, we provide a cover plate 32 for that part of the groove lying beyond the coupling sleeve 26; this cover plate being held to the neck member by a pair of screws 33.

It will thus be seen that we have produced a simple and rugged tool with which protruding annular beads may quickly and accurately be pressed in the walls of pipes or tubes of sheet metal or other ductile material.

While we have illustrated and described with particularity only a single preferred form of our invention, we do not desire to be limited to the exact structural details thus illustrated and described; but intend to cover all forms and arrangements which come within the definitions of our invention constituting the appended claims.

We claim:

1. A beading tool comprising a member adapted to enter a tube, said member having thereon a roller of a contour conforming to the internal trough of the bead to be produced in the tube, said tool also having a second member adapted to overlie the tube at some distance from the latter, an element movably mounted on said second member so as to be adjustable from and toward the first member, a roller carried by said element and provided with an annular groove 75

registering with the first mentioned roller, means for forcibly pressing said element in a direction to bring the rollers together, and a rigid arm on said tool adapted to engage with the periphery of a tube in the tool at a considerable angular distance from the zone of contact between the rollers and the tube, said element having thereon a shoulder for engagement with the end edge of the tube.

10 2. A beading tool comprising a member adapted to enter a tube, said member having thereon a roller of a contour conforming to the internal trough of the bead to be produced in the tube, said tool also having a second member adapted to overlie the tube at some distance from the latter, an element movably mounted on said second member so as to be adjustable from and toward the first member, a roller carried by said element and provided with an annular groove registering with the first mentioned roller, means for forcibly pressing said element in a direction to bring the rollers together, and a rigid arm on said tool adapted to engage with the periphery of a tube in the tool at a considerable angular distance from the zone of contact between the rollers and the tube, said element having a bearing face to engage with the end edge of a tube that is being operated upon by the tool.

30 3. A beading tool comprising a member adapted to enter a tube, said member having thereon a roller of a contour conforming to the internal trough of the bead to be produced in the tube, said tool also having a second member adapted to overlie the tube at some distance from the latter, an element movably mounted on said second member so as to be adjustable from and toward the first member, a roller carried by said element and provided with an annular groove registering with the first mentioned roller, means for forcibly pressing said element in a direction to bring the rollers together, and a rigid arm on said tool adapted to engage with the periphery of a tube in the tool at a considerable angular distance from the zone of contact between the rollers and the tube, the axis of rotation of the outer roller being parallel to the axis of a tube in the tool while the axis of the inner roller lies at a slight angle to a plane containing the aforesaid axes.

50 4. A beading tool comprising a body portion comprising member adapted to enter a stationary tube, said member having thereon a roller of a contour conforming to the internal trough of the bead to be produced in the tube, said body portion also having a second member adapted to overlie the tube at some distance from the latter, an element movably mounted on said second member so as to be adjustable from and toward the first member, a roller carried by said element and provided with an annular groove registering with the first mentioned roller, a handle projecting from said body member in alignment with said element and rotatable about its long axis, connecting means between said handle and said element to cause the element to be forcibly moved in a direction to carry the second roller toward the first roller when the handle is turned in one direction, and a rigid arm on said tool adapted to engage with the periphery of a tube in the tool at a considerable angular distance from the zone of contact between the rollers and the tube and hold the tool and tube in such relative positions that a line extending radially of the tube through the point at which the latter is gripped between the rollers intersects the axes of the two rollers.

5 5. A beading tool comprising a C-shaped member one arm of which is adapted to enter and the other arm of which is adapted to lie outwardly from a tube to be beaded, the first arm having thereon a roller of a contour conforming to the internal trough of the bead to be produced in the tube, an element movably mounted on the second arm of said member so as to be adjustable from and toward the first arm, a roller carried by said element and provided with an annular groove registering with the first mentioned roller, means for forcibly pressing said element in a direction to bring the rollers together, and a third arm on said member adapted to engage with the periphery of a tube in the tool at a considerable angular distance from the zone of contact between the rollers and the tube, said element and said third arm each having a bearing face to engage with the end edge of a tube that is being operated upon by the tool; and the first of said rollers being set with its axis making a small angle with the axis of the tube so that when the tool is swung in a plane at right angles to the axis of the tube, with said third arm in advance, the rollers act to force the tube lengthwise against said bearing faces.

10 6. A beading tool comprising a member adapted to enter a tube, said member having thereon a roller of a contour conforming to the internal trough of the bead to be produced in the tube, said tool also having a second member adapted to overlie the tube at some distance from the latter, an element movably mounted on said second member so as to be adjustable from and toward the first member, a roller carried by said element and provided with an annular groove registering with the first mentioned roller, means for forcibly pressing said element in a direction to bring the rollers together, and a rigid arm on said tool adapted to engage with the periphery of a tube in the tool at a considerable angular distance from the zone of contact between the rollers and the tube, and a stop for the inner end of a tube in the tool, the inner roller facing being set at a slight angle such that the action of the rollers is to force the tube against said stop when the tool is swung around the axis of the tube with said rigid arm in advance.

15 7. A beading tool comprising a head having thereon complementary beading rollers one of which is adapted to enter a tube to be beaded and the other of which is positioned outside of the tube, means to force said rollers together, a handle on said head for swinging the tool bodily around the axis of the tube while the tube is held stationary and a brace projecting from the head and adapted to engage with the exterior of the tube at a point angularly displaced from the zone of contact between the inner roller and the tube and maintain the point of contact between the rollers and the tube on a straight line that intersects the axes of the rollers and of the tube.

20 8. A beading tool comprising a head having thereon complementary beading rollers one of which is adapted to enter a tube to be beaded and the other of which is positioned outside of the tube, and grip the tube at a point which is located on a straight line that intersects the axes of the rollers and of the tube, means to force said rollers together, a handle on said head for swinging the tool bodily around the tube while the latter is held stationary and means to prevent the tool from rocking about the point at which the wall of the tube is gripped by the rollers when the tool

25 30 35 40 45 50 55 60 65 70 75

is swung in one direction in a plane at right angles to the axis of the tube.

9. A beading tool comprising a head having thereon cooperating bead-forming rollers adapted to grip the wall of a tube inserted between them with its axis extending in the general direction of the axes of rotation of the rollers, the parts being arranged to grip the tube as aforesaid at a point that lies on a straight line radial of the tube and intersecting the axes of the rollers, a handle on the head by which the tool may be bodily swung around while the latter is held stationary, means to prevent rocking of the tool relative to the tube when the tool is swung about the tube in one direction and means to force said rollers together to deform the said wall.

10. A beading tool comprising a member adapted to enter a tube, said member having thereon a roller of a contour conforming to the internal trough of the bead to be produced in the tube, said tool also having a second member adapted to overlie the tube at some distance from the latter, an element movably mounted on said second member so as to be adjustable from and toward the first member, a roller carried by said element and provided with an annular groove registering with the first mentioned roller, a handle connected to said members for swinging the tool bodily around the tube while the latter is held stationary, means for forcibly pressing said element in a direction to bring the rollers together, and means to maintain the tool while being swung around the tube in one direction in

the position that maintains the point of contact between the tube and the rollers on a line extending radially of the tube and intersecting the axes of the rollers.

11. A beading tool comprising a member adapted to enter a tube, said member having thereon a roller of a contour conforming to the internal trough of the bead to be produced in the tube, said tool also having a second member adapted to overlie the tube at some distance from the latter and provide it with a handle for swinging the tool about the axis of the tube while the tube remains stationary, an element movably mounted on said second member so as to be adjustable from and toward the first member, a roller carried by said element and provided with an annular groove registering with the first mentioned roller, means for forcibly pressing said element in a direction to bring the rollers together, a rigid arm on said tool, said arm having a part of considerable length adapted to engage with the exterior of a tube in the tool at a considerable distance from the zone of contact between the rollers and the tube and lie parallel with the axis of the tube, the parts being so proportioned that when the wall of the tube is gripped between the rollers and said arm contacts with the exterior of the tube, the point of contact between the tube and the rollers lies in a line intersecting the axes of the tube and the rollers.
